UNITED STATES PATENT OFFICE

2,038,549

METHOD OF COATING METAL

Elgin Carleton Domm, Niles, Mich., assignor to
National-Standard Company, Niles, Mich., a
corporation of Michigan

Original application January 25, 1933, Serial No.
653,549. Divided and this application Septem-
ber 8, 1934, Serial No. 743,282

6 Claims. (Cl. 91—70)

This invention relates to improvements in
method of coating metal.

In the Crapo Patent No. 1,984,335, issued Dec.
11, 1934, is described a method of coating a fer-
rous article by hot-galvanizing it with zinc, and
over that depositing by some other method an
additional coating of zinc or a coating of cad-
mium.

It has now been discovered that a corrosion-
resisting coating of cadmium may be produced
which is considerably more resistant to corrosion,
particularly to the type of which the salt spray is
typical.

At the same time a relatively thin coating may
be produced for equivalent protection to such
corrosion, and such coating may be correspond-
ingly more exactly controlled as to depth and
thickness, by the present method.

The invention is particularly applicable to
coating strands of wire to be used in reinforcing
the bead of a tire. The wire when so used com-
monly acts as a tension-member, and is imbedded
in a rubber or rubber compound. When so used,
the wire is exposed to corrosive and rusting
agents, particularly to moisture which may seep
into the tire.

The drawing shows in diagrammatic form an
embodiment of my invention.

In accordance with the invention, a metal, for
example wire suitable for use in tire beads, is first
hot-dipped to provide a coating of cadmium.
This may be done, for example, by dipping the
wire in hot molten cadmium. Another coating
of cadmium is then put over the first coat by elec-
trolysis or electroplating.

Not only does a double coating applied by the
above-mentioned method give very good corrosion
resistance, but it has been discovered that the
electro-coat tends to fill in the depressions, in the
lower cadmium coat and thus produce a uniform
and smooth coating. This is wholly unexpected.

If desired, copper or other suitable material
may be applied over the corrosive-resistant coat-
ing in order to increase the adhesiveness of the
wire to rubber. It is frequently desirable to
apply such a coating when wire is used as a rein-
forcement for a tire bead.

The new process herein described is especially
useful in procuring a coating of a desired and

uniform thickness. In practice, I give the wire a
hot coat first, and preferably I have this thin.
In the next step, when the coating is put on by
electroplating, the operation can be continued to
give exactly a desired thickness. At the same 5
time the coating requires a smooth, uniform
character which is free from holes, defects, and
the like.

The foregoing description has been given for
clearness of understanding only, and no unneces- 10
sary limitations are to be understood therefrom,
but the appended claims should be construed as
broadly as permissible in view of the prior art.

This application is a division of my co-pending
application Serial Number 653,549, filed January 15
25, 1933.

What I regard as new and desire to secure by
Letters Patent is:

1. The process of coating a ferrous article
which consists in applying to it by the hot-dip 20
process a coating of cadmium, and electrode-
depositing thereon an outer coating substantially
wholly of cadmium.

2. The method of coating a metal to increase
its corrosion resistance comprising first applying 25
to it molten cadmium, and then applying a sec-
ond coating of cadmium by electroplating over
the first coating.

3. The method of producing a ferrous tire-
bead reinforcement wire of uniform corrosion- 30
resistance which comprises first coating a ferrous
wire with cadmium by the hot-dip process, and
then electroplating cadmium upon the hot-dip
wire to produce a uniform coating of desired
thickness. 35

4. A coated ferrous article, comprising a fer-
rous base having a hot-dipped coating of cad-
mium thereon, and over that an electrodeposited
coating substantially wholly of cadmium.

5. A coated ferrous wire, comprising a ferrous 40
base wire having a hot-dipped coating of cad-
mium thereon, and over that an electrodeposited
coating substantially wholly of cadmium.

6. A coated tire bead wire comprising a ferrous 45
base wire having a hot-dipped coating of cad-
mium thereon, an electrodeposited coating sub-
stantially wholly of cadmium thereon, and having
a coating of rubber vulcanized thereto.

ELGIN CARLETON DOMM.
